ELMER E. LANE, OF BEVERLY, MASSACHUSETTS, ASSIGNOR TO UNITED SHOE MACHINERY COMPANY, OF PATERSON, NEW JERSEY, A CORPORATION OF NEW JERSEY.

BUFFING-MACHINE.

1,168,514.

Specification of Letters Patent. Patented Jan. 18, 1916.

Application filed August 3, 1912. Serial No. 713,115.

To all whom it may concern:

Be it known that I, ELMER E. LANE, a citizen of the United States, residing at Beverly, in the county of Essex and State 5 of Massachusetts, have invented certain Improvements in Buffing-Machines, of which the following description, in connection with the accompanying drawings, is a specification, like reference characters on the drawings indicating like parts in the several 10 figures.

This invention relates to buffing machines and is herein illustrated as embodied in a machine for buffing soles, box toes and similar articles which are to be used in the manufacture of boots and shoes.

Hitherto in machines of this class the leather piece has been passed first between a feed roll and a buffing roll whereby the buffing operation has been performed and then between a presser roll and a brush whereby the dust that clung to the leather piece has been removed. It has been found, however, first, that the forward end of the leather 20 piece tended to curl up after emerging from between the feed roll and the buffing roll and, second, that some of the leather pieces were so short that their forward ends failed to reach the presser roll and the brush by 25 the time their rear ends had emerged from between the feed roll and buffing roll. In either case the leather piece was not fed properly through the machine.

In order to overcome these disadvantages 35 and to improve the machines of this type generally, one feature of the present invention consists in providing a guide between the buffing means, constituted in the illustrative machine by the feed roll and buff- 40 ing roll, and the cleaning means constituted by the presser roll and brush. This guide may take the form of a plate or roll, and in the illustrated embodiment of the invention is mounted so as to be moved toward and 45 from the work in unison with the feed roll.

It is desirable in machines of this class that the feed roll be yieldingly pressed to-

ward the buffing roll and at the same time be adjustable toward and from said buffing roll. When, however, stops are provided one at each end of the feed roll arranged to contact with the bearings of said roll and thereby limit the movements caused by the springs, it has been difficult to insure that the axis of the presser roll should be parallel 50 in its various adjusted positions to that of the buffing roll. In the illustrated machine these stops are dispensed with and a single stop provided which contacts with the treadle by which the presser roll may be raised. 60 This stop is adjustable, and by adjusting it the distance between the feed roll and the buffing roll may be varied without disturbing the parallel relation of the axis of the two rolls.

These and other features of the invention including certain details of construction and combinations of parts will be described in connection with the accompanying drawings and pointed out in the appended claims.

Referring now to the accompanying drawings, Figure 1 is a front elevation of a machine in which the present invention is embodied; Fig. 2 is a section of the upper portion of the machine; Fig. 3 is an elevation 75 of a guide for the stock, certain adjacent portions of the machine being shown in section; and Fig. 4 is a plan of the parts shown in Fig. 4.

The buffing roll 2 comprises a suitable 80 body portion having a removable covering of abrasive material and is secured upon a horizontal shaft 4 which is mounted in bearings carried by the side plates 6. The shaft 4 is arranged to be rotated and longitudinally reciprocated by means which will be hereinafter described. With this movement of the shaft 4 the buffing roll is given a compound abrading movement such that different portions of its acting surface travel 85 in intersecting paths, the result being that a very smooth surface is imparted to the work. The side plates 6 rest upon a base plate 8 and are secured thereto by bolts 10,

said base plate 8 being secured upon the top portion of a casting 12 which is part of the base of the frame of the machine.

The feed roll 14 is arranged above the buffing roll and comprises a sleeve 16 of yielding material, such as rubber, mounted upon a metal core 18 secured upon a horizontal shaft 20 which in turn is mounted in tubular sleeves 22 which are carried by blocks 24 slidably mounted in vertical guideways 26 in the side plates 6. The blocks 24 are yieldingly pressed toward the buffing roll by means of springs 28 confined between the blocks and the lower ends of adjusting screws 30 threaded in cap pieces 32 extending across the top portions of the guideways 26 and secured to the side plates 6.

The work support comprises a flat plate 38 which is arranged to support the work 20 in position to be fed between the feed roll and the buffing roll and to co-operate with the feed roll to position the work in proper relation to the buffing roll. The plate 38 extends into close proximity to the surface 25 of the feed roll so that the article to be buffed is pressed between the roll and the said plate and its lower surface brought into a position to be acted upon by the buffing roll. The position of the lower surface of 30 the article is determined by the plate 38 which is adapted to act as a gage plate to maintain the article in position to be operated upon regardless of irregularities in its shape or thickness. The plate 38 is arranged for vertical adjustment toward and from the periphery of the feed roll, and for adjustment in the general direction of the line of feed of the work in order that the plate may be so positioned that the work 40 will be subjected to the proper degree of pressure as it passes between the feed roll and the plate. To this end the plate 38 is adjustably secured upon the top of a support 40 by screws 42 extending through slots 45 in the plate and into the support, the slots being so arranged that upon loosening the screws the plate may be adjusted relatively to its support in a direction at a slight angle to the line of feed of the work. It will thus 50 be evident that the work is distorted by being gripped between the plate 38 and the yielding feed roll and that while so held the reciprocating motion of the buffing roll will not move it laterally. The support 40 is 55 mounted upon the top of a vertical plate 43 which is removably clamped against vertical surfaces 44 formed on the frame of the machine as by means of bolts 46 extending through vertical slots in the plate 43 and tapped into the frame of the machine. The vertical plate 43 is provided at its lower edge with two lugs 48 arranged on opposite sides thereof through which extend vertical adjusting screws 50 which bear with their

lower ends against the base plate 8 of the machine. With this arrangement by turning the screws 50 the vertical plate 43 may be adjusted vertically and consequently the work supporting plate 38 which is carried thereby may be adjusted toward and from 70 the periphery of the feed roll. As is usual in machines of this class the rolls are enclosed in a hood which is connected with the exhaust pipe whereby the dust generated during the operation of the machine is removed. In the present case the plate 43 forms a portion of the wall of the hood, and in order to prevent the suction from being broken by the raising of the plate 43, a gate 51 is set loosely in a groove in the lower 80 edge of said plate, said gate remaining at all times in contact with the plate 8. The gate, in effect, is a continuation of the plate and serves automatically to lengthen and shorten the plate according to the direction 85 in which the plate is adjusted.

The brush for cleaning the buffed surface of the work is a rotary one, 52, secured to a shaft 54 which is arranged to be rotated in a direction such that the brush assists in feeding the work. The shaft 54 is mounted in bearing blocks 56 which are arranged in guideways formed in the side plates 6 of the machine. Each of the blocks 56 is provided with a threaded rod 58 which extends downwardly through openings formed in the bottom walls of the guideways and into recesses 60 arranged below the guideways. A pair of nuts 62 and 63 threaded upon each of the rods 58 and arranged to engage the 100 top and bottom surface of each recess 60 serve to secure the blocks 56 in adjusted position. With this construction the blocks 56 may be adjusted to bring the brush into proper position with respect to the lower 105 surface of the work after the work has been subjected to the operation of the buffing roll.

To hold the work in operative engagement with the brush during its movement there 110 is provided a freely rotatable roller 62 arranged substantially over the brush. The roller 62 is secured upon a shaft 64 rotatably mounted in bearings carried by a yoke 66 the arms of which are provided with split 115 clamps 70 by which they are respectively clamped upon the tubular sleeves 22, the ends of said sleeves being turned down to form cylindrical bearings for said clamps. Upon loosening the clamps 70 the yoke 66 120 may be swung about the sleeves 22 to place the roller 62 in adjusted position. In order to prevent the stock from curling up between the feed roll 16 and the brush roll 62 a guide 61 having upwardly extending ends 125 63 is clamped to the bar 66 by bolts 65; and in order that said guide may be adjusted to provide for wear of the roll or for stock of

different thickness, slots 67 are formed in said ends.

In buffing leather articles it is sometimes desirable to buff only a portion of the article.

- 5 Accordingly, the present machine has provision whereby a portion of the work may be passed through the machine without being buffed and thereafter the remaining portion brought into operative relation with the 10 buffing tool. In accordance with a convenient construction there is provided means under control of the operator for moving the feed roll away from the buffing roll in order that the portion of the work 15 which is not to be buffed may be passed by hand between the rolls and out of contact with the buffing roll, the construction being such that thereafter the feed roll may be lowered to press the remaining portion of 20 the work into contact with the buffing roll.

The means for raising the feed roll comprises a suitable treadle 72 connected by a pair of links 74, one upon each side of the machine, with the front ends of horizontally 25 disposed levers pivoted at their middle portions, as indicated at 76, upon opposite sides of the base plate 8, and links 78 pivotally connecting the inner ends of the horizontal levers with the blocks 24 which carry the 30 feed roll. With this construction it will be seen that upon pressing the treadle 72 the feed roll will be raised in opposition to the springs 28, and upon releasing the treadle said springs will move the feed roll 35 into operative relation to the buffing roll. It is very desirable that the feed roll 14 be adjustable toward and from the buffing roll 2 and that the axis of said feed roll be maintained at all times parallel to that of 40 the buffing roll. Accordingly a set screw 69 threaded through a boss 71 on the frame of the machine and provided with a lock nut 73 is arranged to contact with the upper surface of the treadle 72 and thereby limit 45 the downward movement of the feed roll 14. In order to permit the proper adjustment of the feed roll to bring it into parallel relation with the buffing roll turn buckles 176 are provided in the links 74. With this 50 construction after the feed roll has once been placed in parallel relation with the buffing roll by manipulating the turn buckles, said parallel relation will be maintained in all the adjustments of the screw 69. 55 It sometimes happens that the piece of stock tends to turn downwardly after its front end emerges from between the feed roll and buffing roll; and in order to provide for such a contingency a support 75 provided 60 with perforations 77 is mounted in the rear of said rolls, the purpose of said perforations being to permit any dust which may be carried on to the support to be drawn away. It should here be noted that the sup-

port 75 has a downwardly extending portion which serves as a guard to keep the dust from being drawn into the brush.

The mechanism for operating the moving parts of the machine may be of any convenient type and will be briefly indicated. 70 The mechanism for rotating the buffing roll comprising a pulley 97 secured on the end of the shaft 4, a pulley 98 upon the power shaft 100 and a belt passing over these pulleys. A belt tightening pulley 102 positioned to engage the face of the driving belt is arranged to be adjusted by a hand lever 104. For rotating the feed roll there is provided a sprocket secured upon the power shaft 100, a large sprocket secured upon 75 the horizontal shaft 110, a chain 108 passing over these sprockets, a pinion 112 secured upon the end of the shaft 110, a gear 114 meshing with said pinion and secured upon the end of a shaft 116, a sprocket secured upon this shaft, a sprocket 120 rotatably mounted upon a stud secured in one of the side plates 6, a chain 122 passing over these sprockets, a small sprocket arranged for rotation with the sprocket 120, 80 a sprocket 126 secured upon the end of the feed roll shaft and a chain 124 connecting these sprockets. The mechanism for rotating the brush and the fan comprises a pulley 128 secured upon the end of the power shaft 100, a pulley 130 secured upon 85 the fan shaft and a belt passing over these pulleys. The power shaft 100 is provided with the usual fast and loose pulleys 136 and 138 and belt shifter 140. The driving connections have been indicated briefly and have not been illustrated more fully since they have been used hitherto, are ordinary 90 mechanical contrivances, and their details form no part of the present invention. It will be understood, however, that the feed roll and buffing roll are rotated in opposite directions as is usual and that the chain drive of the feed roll permits said roll to be raised when desired by depressing the treadle 72. 95

To impart a longitudinal reciprocating movement to the buffing roll there is secured upon the end of the shaft 116 a cam disk 144 having a cam groove that receives a roller 146 carried by the lower end of a 115 cam lever 148 pivoted intermediate its ends between lugs 150 projecting from the frame of the machine. The upper end of the lever 148 is provided with rollers 152 arranged to engage the sides of the groove formed in a hub 154 carried on the end of the buffing roll shaft. With this construction the buffing roll reciprocates longitudinally as it rotates so that different portions of its acting surface travel in intersecting paths. Where one 120 roller is used in place of two rollers 152 the direction of rotation of said roller is reversed every time the roller is moved into

4
contact with one or the other side of the groove in which it runs. There is thus produced a great amount of friction which rapidly wears the parts. With the present 5 construction it will be noted that the rollers 152 rotate in opposite directions but that each roller considered by itself rotates in one direction only.

The purpose of the sole guide 61 shown in 10 Fig. 2 has been referred to above. It sometimes happens, however, that short pieces, such, for example, as box toes, are operated upon which are not long enough to extend 15 from the feed roll 16 to the brush roll 62 and for that reason are not fed properly to the machine. In such cases, or in all cases, if preferred, the mechanism illustrated in Figs. 5 and 6 may be substituted for the yoke 66 and the parts carried by it.

20 A yoke 121 is provided with split bearings 123 similar to the bearings 70 and similarly held upon the sleeve 22 by pinch screws 125, and a second yoke 127 has split bearings 129 at the ends of its arms which are held loosely 25 upon the hubs of the roll by screws 131 so that said second yoke is freely movable about the axis of the shaft 20. The yoke 121 carries a roll 133 which is similar to the roll 62 and similarly mounted. Between the rolls 30 14 and 133 is a guide in the form of an auxiliary guide roll 135; and in order that this roll may be driven from the feed roll 14 and at the same time may be adjusted toward and from the work to compensate for wear of 35 the feed roll or for the thickness of the stock, the following mounting is provided.

The shaft 137 of the guide roll 135 is rotatably mounted in arms 139 formed on the split bearings 129, said arms being thus a 40 part of the yoke 127 and movable therewith. The shaft 137 is also mounted in a third yoke 141 having arms provided with downward extensions 143 in the lower ends of which the ends of the shaft 137 are rotatably held. 45 The rear extension of the yoke 141 lies in a depression in the rear part of the yoke 121, a set screw 145 being threaded through said extension and abutting the surface of the depression in the yoke 121, and a lock nut 147 serving to hold said set screw in adjusted 50 position. In order to maintain the lower end of the set screw at all times in contact with the yoke 121 a pin 149 on the yoke 141 is connected through a spring 151 with a pin 55 153 carried by the yoke 121. It is thus possible by manipulating the set screw 145 to adjust the auxiliary guide roll 135 toward or from the stock. In order to drive said auxiliary roll 135 an idle roll 155 has bearings 157 which are slidably mounted in slots 159 formed in the extensions 143 of the yoke 141, set screws 161 being threaded through said 60 yoke and extending into sockets in said bearings. This provides means for forcing the

idle roll 155 against the guide roll 135. Lat- 65 eral movement of said idle roll to maintain it in contact with the feed roll 14 is brought about by springs 163 each having one end bearing against the hollow plunger 165 and the other end against the hollow adjusting 70 screw 167. The plungers are slideable in sockets in the screws, and the screws are threaded into bores in the yoke 121. With this construction the idle roll 155 may be 75 adjusted to contact with the guide roll 135 in any of its positions by manipulating the set screw 161.

In order to insure that the material shall lie flat during its passage through the machine a presser 169 carried at the lower ends 80 of adjusting screws 171 extends between the rolls 14 and 135; and a similar presser 173 carried by adjusting screws 175 extends between the rolls 133 and 135.

The operation of the machine is as fol- 85 lows:—The turn buckles 76 are manipulated to adjust the axis of the feed roll 14 into a position parallel to that of the buffing roll 2, after which the set screw 69 is manipulated to set the rolls at the desired distance apart. 90 If the guide 61, shown in Fig. 2, is being used, said guide is adjusted vertically by loosening the bolts 65 and moving the guide to the proper position. If the guide roll 135 shown in Fig. 5 is being used the set screws 95 145 and 161 are manipulated to adjust said roll. A sole or other article is then fed to the machine, being subjected first to the action of the buffing roll 2 and then to the action of the brush 52.

100 Although the invention has been set forth in connection with a particular machine, it should be understood that the invention is not limited in the scope of its application to the particular machine shown and described.

Having thus described my invention, what I claim as new and desire to secure by Letters Patent of the United States is:—

1. In a leather buffing machine the combination with a buffing roll and a feed roll 110 adjustable toward and from said buffing roll, of a guide roll located at the rear of the feed roll and adjustable therewith.

2. In a leather buffing machine the combination with a buffing roll and a feed roll 115 adjustable toward and from said buffing roll, of a guide roll located at the rear of the feed roll and adjustable therewith and means for adjusting said guide roll with respect to said feed roll.

3. In a leather buffing machine the combination with a buffing roll, a feed roll and bearings for said feed roll which are adjustable toward and from said buffing roll, of a yoke fast to said bearings, a guide carried by said yoke and means for adjusting said guide with respect to said bearings.

4. In a leather buffing machine the combi-

- nation with a buffing roll, a feed roll and 5
bearings for said feed roll which are ad-
justable toward and from said buffing roll,
of a yoke fast to said bearings, an auxiliary
roll carried by said yoke and means for ad-
justing said auxiliary roll with respect to
said bearings.
5. In a leather buffering machine the combi-
nation with a buffing roll, a feed roll and
10 bearings for said feed roll which are ad-
justable toward and from said buffing roll,
of a yoke fast to said bearings, an auxiliary
roll carried by said yoke and a presser lo-
cated between said feed roll and auxiliary
15 roll.
6. In a leather buffering machine the combi-
nation with a buffing roll, a feed roll and
bearings for said feed roll which are ad-
justable toward and from said buffing roll,
20 of a yoke fast to said bearings, a guide roll
carried by said yoke, means for adjusting
said guide roll with respect to said bearings,
and means for rotating said guide roll from
said feed roll.
- 25 7. In a leather buffering machine the combi-
nation with a buffing roll, a feed roll and
bearings for said feed roll which are ad-
justable toward and from said buffing roll,
of a yoke fast to said bearings, a guide roll
30 carried by said yoke, means for adjusting
said guide roll with respect to said bearings,
an idle roll between said feed roll and guide
roll and means for adjusting said idle roll.
8. In a leather buffering machine the combi-
35 nation with a buffing roll, a feed roll and
bearings for said feed roll which are ad-
justable toward and from said buffing roll,
of a yoke fast to said bearings, a roll-sup-
porting member loose upon said bearings, a
40 spring connecting said yoke and member and
a guide roll carried by said member.
9. In a leather buffering machine the combi-
nation with a buffing roll, a feed roll and
bearings for said feed roll which are ad-
45 justable toward and from said buffing roll,
of a yoke fast to said bearings, a roll-sup-
porting member loose upon said bearings, a
spring connecting said yoke and member, a
guide roll carried by said member, and
50 means for adjusting said guide roll with
respect to said member.
10. In a leather buffering machine the combi-
nation with a buffing roll, a feed roll and
bearings for said feed roll which are ad-
55 justable toward and from said buffing roll,
of a yoke fast to said bearings and a roll-
supporting member in the form of a two-
part yoke angularly movable about said
bearings, a shaft connecting the parts of
60 said two-part yoke and a guide roll mounted
on said shaft.
11. In a leather buffering machine the combi-
nation with a buffing roll, of a feed roll
and bearings for said feed roll which are ad-
- justable toward and from said buffing roll, 65
of a yoke fast to said bearings, a roll-sup-
porting member in the form of a two-part
yoke angularly movable about said bearings,
a spring connecting said yoke and support-
ing member, a shaft connecting the parts of 70
said two-part yoke, and a guide roll mounted
on said shaft.
12. In a leather buffering machine the combi-
nation with a buffing roll, a feed roll ad-
justable toward and from said buffing roll, 75
a brush to clean the surface of the work
after it has been buffed, a roll arranged to
press the work against the brush, said brush
roll being adjustable with said feed roll, of
a guide adjustable with said feed roll and 80
brush roll, and means for adjusting said
guide with respect to said rolls.
13. In a leather buffering machine, a buffing
roll, a feed roll, springs tending to move
said feed roll toward said buffing roll and 85
means for limiting said movement, said
means comprising a treadle connected with
said feed roll and a stop for limiting the
movement of said treadle.
14. In a leather buffering machine, a buffing 90
roll, a feed roll, bearings for said feed roll,
a treadle, means for connecting said bearings
with said treadle whereby movement of the
treadle moves the bearings, and an adjust-
able stop to limit the movement of the 95
treadle and thereby of the bearings.
15. In a leather buffering machine, a buffing
roll, a feed roll, yielding means for causing
one of said rolls to move toward the other,
a treadle, means for connecting said movable 100
roll with said treadle whereby depression of
said treadle moves said roll, and a stop ar-
ranged to contact with said treadle.
16. In a leather buffering machine the combi-
nation with a feed roll, a buffing roll, a 105
work support and a hood inclosing said rolls,
said hood comprising an adjustable plate
upon which said support is mounted, of
means for automatically lengthening and
shortening said plate according to the direc- 110
tion of the adjusting movement.
17. In a leather buffering machine the combi-
nation with a feed roll, a buffing roll, a 115
work support, and a hood inclosing said roll,
said hood comprising an adjustable plate
upon which said support is mounted, of a
gate mounted in the lower edge of said plate
and adapted to form a continuation of said
plate when said plate is raised.
18. In a leather buffering machine, a rotary 120
buffing roll and means for reciprocating said
roll, said means comprising a member con-
nected with said roll and provided with a
cam way, two rollers located therein and
arranged to contact each with one wall only 125
of said cam way, a carrier for said rollers,
and means for actuating said carrier.
19. In a leather buffering machine, a rotary

buffing roll and means for reciprocating said roll, said means comprising a member connected with said roll and provided with a track, a roller arranged to contact with one wall of said track, a second roller arranged to contact with the other wall, and means for moving said rollers bodily to cause them to be alternatively operative.

In testimony whereof I have signed my name to this specification in the presence of 10 two subscribing witnesses.
